UNITED STATES PATENT OFFICE

JOHN LAUTERBACH, OF UTICA, NEW YORK, ASSIGNOR TO HORROCKS-IBBOTSON COMPANY, OF UTICA, NEW YORK, A CORPORATION OF NEW YORK

DESIGN FOR A FISHING REEL

Application filed November 25, 1931. Serial No. 41,859. Term of patent 14 years.

To all whom it may concern:

Be it known that I, JOHN LAUTERBACH, a citizen of the United States, residing at Utica, in the county of Oneida and State of New York, have invented a new, original, and ornamental Design for a Fishing Reel, of which the following is a specification, reference being had to the accompanying drawings, forming part hereof.

Fig. 1 is a rear side view of a fishing reel showing my design.

Fig. 2 is an edge view of said fishing reel.

Fig. 3 is a front side view of said reel.

I claim:

The ornamental design for a fishing reel as shown.

JOHN LAUTERBACH
